CHUTE

Isaac T. Dobbs, Minneapolis, Minn.

Application September 29, 1936, Serial No. 103,159

4 Claims. (Cl. 193—6)

This invention relates to chutes. An object of the invention is to provide a chute which may be used for any and all purposes requiring the use of a chute.

5 An object of the present invention is also to provide an improved extensible chute wherein the sections thereof telescope to reduce the chute to such a size as to require but small storage space when not in use, or which chute can be extended to the desired length in accordance with the requirements as to length, and as determined by the distance between the point of location of the material and the point to which the material is to be directed through the medium of the chute.

10 15 A further object of the invention is to provide a chute composed of telescoping sections and characterized by having the sections tapered in such a manner that the chute may be extended in a straight line or at an angle as found desirable.

20 The invention, together with its objects and advantages will be best understood from a study of the following description taken in connection with the accompanying drawings, wherein:

25 Figure 1 is a top plan view of the improved chute, the same being shown extended in a straight line.

Fig. 2 is a side elevational view of the chute.

Fig. 3 is an elevational view of the chute at the inner end thereof.

30 Fig. 4 is an end elevational view of the section of the chute forming the discharge end of the chute, and

Fig. 5 is a detail sectional view taken substantially on the line 5—5 of Fig. 1.

35 Referring to the drawings by reference numerals, it will be seen that the improved chute comprises a plurality of telescoping sections including an inlet section 5 a discharge end section 6, and any desired number of intermediate sections 7.

40 Each of the sections 5, 6, and 7 have flanged sides and taper from the rear to the front, and these sections are secured together by means of 45 slots 8 formed in the flanges 9 of the sides 10 of the respective sections 5 and 7, and the fixed rivets 11 provided at one end of the flanges of all of the sections, with the exception of the section 5 and extending through the slots 8 of the sections 50 5 and 7, as clearly shown.

To permit a complete telescoping of the sections for the full length of the respective sections, the flanges 9 of sections 5 and 7 have the front ends of said sections provided with bells 55 or struck-up portions 12 formed by pressing por-

tions of the flanges upwardly out of the plane of the flanges, the bells serving to accommodate the heads of the rivets, in a manner to permit the heads of the rivets of each section to start under the flanges of the next preceding section 5 when the sections are telescoped for reducing the length of the chute. It will be apparent that when the heads of the rivets are thus placed under the fluted or bell-equipped ends of the flanges, there is nothing to prevent movement of 10 the several sections as required to telescope said sections.

The section 5 at the front or intake end of the chute is flared at its intake as at 13 and is reinforced thru the medium of an angle bar 14 15 that extends across the bottom of the chute section and up alongside the sides of said chute section being riveted to the bottom and sides or otherwise positively secured thereto.

20 Intermediate its ends the angle bar 14 is provided with spaced notches 15 as shown in Fig. 3, through the medium of which the chute may be suspended at its intake end from a wagon box or the like through the medium of hooks, chain, or similar means.

25 Also to prevent "creeping" of the chute at the discharge end thereof, there are suitably secured to the under side of the bottom of the section 6 of the chute, straps 16 having downturned ends 17 forming cleats to engage the ground to provide, as it were, an anchor for the discharge end section 6 of the chute. It will be further appreciated that with the cleats 17 engaged with the ground, the several sections of the chute will be 30 retained at the desired position of adjustment, thereby preventing accidental telescoping of the sections or unintended extension of the chute.

35 It will be further noted that the flanges 9 of each section taper longitudinally in proportion to 40 the amount of taper of the respective chute sections. This will permit the slots 8 to remain parallel at all points, leaving sufficient stock to retain the proper supporting strength in the flanges.

45 From the above it will be seen that I have provided a strong, durable chute composed of telescoping sections and which can be lengthened or shortened as found desirable; and which when the sections are completely telescoped, will require 50 but comparatively small storage space.

Having thus described the invention, what is claimed as new is:—

55 1. An extensible chute consisting of a plurality of telescoping trough sections having tapering

sides, the sides of said sections being provided with lateral outstanding tapering flanges having longitudinal slots formed therein, and rivets secured to the flanges of the respective sections and engaging in the slots of the flanges of the next succeeding section for connecting the sections together, and the flanges of each section at one end thereof having struck-up portions accommodating the rivets of the next preceding section, when the sections are telescoped.

5 2. An extensible chute consisting of a plurality of telescoping trough sections having tapering sides, the sides of said sections being provided with lateral outstanding flanges having longitudinal slots formed therein, rivets secured to the flanges of the respective sections and engaging in the slots of the flanges of the next succeeding section for connecting the sections together, and the flanges of the respective sections 10 having bells at one end thereof to accommodate the heads of the rivets of the next preceding section.

15 3. An extensible chute consisting of a plurality of telescoping trough sections having tapering sides, the sides of said sections being provided with lateral outstanding flanges having longitudinal slots formed therein, rivets secured to the flanges of the respective sections and engaging in the slots of the flanges of the next succeeding section for connecting the sections together, the flanges of the respective sections 20 having bells at one end thereof to accommodate the heads of the rivets of the next preceding section.

25 30

one end thereof to accommodate the heads of the rivets of the next preceding section, said sections including an intake section having a flared intake end, and a reinforcing bar secured to said flared intake end and extending across from the bottom and sides of the last-mentioned section at the mentioned end thereof.

4. An extensible chute consisting of a plurality of telescoping trough sections having tapering sides, the sides of said sections being provided with lateral outstanding flanges having longitudinal slots formed therein, rivets secured to the flanges of the respective sections and engaging in the slots of the flanges of the next succeeding section for connecting the sections together, the flanges of the respective sections having bells at one end thereof to accommodate the heads of the rivets at the next preceding section, said sections including an intake section having a flared intake end, a reinforcing bar secured to 15 said flared intake end and extending across the bottom and sides of the last-mentioned section at the mentioned end thereof, and said reinforcing bar being provided with notches at an intermediate portion thereof for engagement with attaching means for anchoring said intake end of the chute to a support, and said chute also including a discharge section, and anti-creeping devices on the under side of the discharge section of the chute, as and for the purpose specified.

ISAAC T. DOBBS.
